CLAIM

The ornamental design for an equipment powerhead as shown and described.

DESCRIPTION

FIG. 1 is a front perspective view of an equipment powerhead, according to the present invention;

FIG. 2 is a left side elevational view of the equipment powerhead of FIG. 1;

FIG. 3 is a right side elevational view of the equipment powerhead of FIG. 1;

FIG. 4 is a front elevational view of the equipment powerhead of FIG. 1;

FIG. 5 is a rear elevational view of the equipment powerhead of FIG. 1;

FIG. 6 is a top plan view of the equipment powerhead of FIG. 1; and,

FIG. 7 is a bottom plan view of the equipment powerhead of FIG. 1.

The dashed lines in the Figures are for environmental purposes only and do not form a part of the claimed design.
